BURNER

Frank W. Ofeldt, McKeesport, Pa., assignor to
Homestead Valve Manufacturing Company,
Coraopolis, Pa., a corporation of Pennsylvania

Application July 18, 1936, Serial No. 91,405

10 Claims. (Cl. 158—53)

This invention relates to burners generally and more particularly to burners which are provided with means for preheating or volatilizing fluid fuel and the method of operating the same.

5 This invention may be conveniently applied to heaters that require uniform distribution of the burning gases and accurate timing of combustion within the combustion chamber. Heaters that may advantageously employ these features 10 are found in the coil heater art for water heaters, spray or atomized heaters and the like, some of which are disclosed in my Letters Patent No. 1,925,643, No. 1,970,971, and applications for Letters Patent Serial No. 36,290, filed August 15, 1935 15 and Serial No. 88,106, filed June 30, 1936, and others referred to therein.

In coil heaters the form of the coils and the manner in which they are placed within the combustion chamber determine the baffling characteristics for distributing and guiding the flame. To vary the control of the flame hitherto it has been necessary to reform or rearrange the coils or parts which are being heated. As a practical consideration it is usually necessary to construct 25 a new heater for this purpose, which adds expense.

The principal object of this invention is the provision of a new and improved deflector for controlling the distribution and timing the combustion of the flame.

Another object is the provision of improved means for preheating or vaporizing a fluid fuel prior to discharging it against the deflector, thereby permitting accurate control thereof.

35 This invention also contemplates a novel jet and priming device for initially starting combustion.

Other objects appear hereafter.

In the accompanying drawing wherein I have 40 illustrated a practical embodiment of the principles of my invention:

Fig. 1 is a plan view of the burner assembly comprising my invention.

Fig. 2 is a side elevation of the burner shown 45 in Fig. 1.

Referring to the drawing, 1 represents the base of a combustion chamber or outer casing having an aperture 2 through which the burner assembly 3 is arranged to extend into the combustion 50 chamber. The burner assembly comprises the flame guiding ring casting 4 having oppositely disposed outwardly extending arms 5. Adjacent their outer ends the arms 5 are provided with the holes 6 for receiving the bolts 7, arranged to 55 secure the burner assembly to the base 1 by the

nuts 8. 9 represents spacer members around the bolts 7 between the base 1 and the arms 5 for maintaining spaced relation between these parts to reduce heat conductivity therebetween.

The ring casting is provided with aligned slots 10 in the same plane as the outwardly extending arms 5. These slots are arranged to receive the outer ends of the deflector member supporting arms 11. Where the arms 5 are joined to the ring 4 I provide the bosses 12. These bosses are 10 drilled to receive the bolts 13 which pass through the outer ends of the deflector supporting arms 11 for securing the same to the ring casting 4 as by the nuts 14.

The arms 5 may be strengthened by means of 15 the webs 15 which extend between the bosses 12 and the arms 5. These strengthening webs also aid in providing radiating surfaces for cooling the ring casting. To this end the ring casting 4 may be provided with the radially disposed radiating 20 fins, as indicated in dotted lines in Fig. 1 at 16.

The deflector supporting arms 11 extend radially from the flame deflecting member 17 and are provided with the V-shaped depending flanges 18 which strengthen said arms and prevent tur- 25 bulence of the flame as it passes therearound. The deflecting member 17 is preferably hollow. The lower portion 19 of the deflector is preferably spherical and the upper portion 20 cylindrical.

Thus combustible gases impinged on the under 30 surface thereof will be spread uniformly there- around. The spherical surface also dispenses with the necessity of accurately adjusting the center of the impinging gases to strike the center 35 of the deflector. Thus slight misalignment of the burner nozzle caused by assembly or by relative expansion of the parts due to different materials or due to different temperatures will not impair the proper function of the deflector. I am thus 40 enabled to avoid the difficulties arising from the use of conical or pointed deflectors.

One arm 11 is provided with a boss 21 which is drilled to receive and hold one end of the tube forming the fuel preheating coil 22. The fuel 45 being fed to the heating coil is arranged to pass from the fuel supply up through the vertical portion 23 of the coil. Near to the top of the vertical portion 23 the first coil turn 24 is formed. The uppermost position of the coil 22 occurs at sub- 50 stantially the first half of the coil turn 24 as indicated at 25. The coil then descends and is wound around the cylindrical portion 20 of the deflector 17. The last turn 26 of the coil is di- 55 rected toward the boss 21. The tube is then

formed to pass down through the boss as shown at 21.

The tubing extends below the ring casting 4 as shown at 28 and is arranged to extend radially inwardly toward the center of the deflector 17.

29 represents a nozzle secured to the end of the tube and provided with the port 30 arranged to direct the fuel against the center of the spherical surface 19 of the deflector 17.

10 The deflector 17 is provided with the radially projecting lugs 31, 32 and 33 arranged to support the lower side of the coil 22 as it winds down around the deflector.

It will be noted from Fig. 1 that the coil turn 15 24 extends out in the direct path of the burning gases and is subjected to considerable heat. Assuming that oil under pressure is used for fuel, it will flow from the source of supply up through the tube 23 through the flame guiding ring 4 to 20 the coil turn 24 and therearound to the highest point 25. During this time it will have been heated sufficiently to volatilize. The volatilized fuel then passes around the balance of the turn 24 and through the coil, the tube 28 to the nozzle 29, 25 from whence it is expelled out the opening 30 of the jet. The volatilized fuel becomes superheated as it passes through the coil 22. This promotes quick and efficient combustion.

The highly heated fuel impinging against the 30 spherical surface and being deflected therearound has been found not to support combustion until it reaches the deflector arms 11 and the lugs 31 and 33, as the flame propagation is not as fast as the velocity of the gas over the spherical surface.

35 By placing the lugs or ears 34 on the spherical surface of the deflector I am enabled to control the timing of the initial flame combustion. These small lugs on the spherical surface create a vortex in the flow of the fuel forming a turbulent 40 action therein which causes ignition of the fuel at the tips of the lugs. Thus the position of the lugs on the spherical surface 19 determines the time at which combustion of the fuel is started.

As the fuel strikes the spherical surface it is 45 distributed uniformly therearound and is guided up through the ring 4 past the fuel heating coil 22. As the fuel supply continues to flow through the coil 22 it becomes heated, vaporizes and is discharged from the nozzle. The deflector 17 and the coil 22 become quite hot, which aid in maintaining the heating cycle.

50 35 represents a priming pan which may be conveniently supported from the burner structure by means of the arm 36 secured at its free end under the nut 14 on the bolt 13 which holds the deflector to the ring casting 4. The priming pan may be provided with fuel and a wicking, such as waste, which when ignited heats the nozzle and the lower portion of the fuel pipe and the fuel therein. This 55 continues until the burner flame heats the fuel in the coil 22 sufficiently to permit continuous operation thereof.

A notch 37 is formed in the bottom edge of the 60 depending flange 18 adjacent the deflector 17. This notch provides a break in the lower edge of each flange and permits that portion of the combustible gases and the flame that is adjacent the deflector 17 to pass up along both sides of the depending flanges 18 and the arms 11. If the 65 lower edges of these flanges were permitted to extend horizontally to the deflector a portion of the gases and the flame would roll therealong toward the flame guiding ring 4 and be deflected downwardly, creating a rotary turbulence that would 70 have a detrimental effect on the burning fuel.

Thus by abruptly changing the contour of the flanges 18 adjacent the deflector 17 so that it extends upwardly toward the deflector, that portion of the fuel and flame passing therearound is carried by its own velocity to a point above the 5 lower edge of the flange and therefore travels undisturbed to the combustion zone.

I claim:—

1. In an oil burner, the combination of a flame guiding ring, a deflector positioned concentrically 10 within said ring and having an under arcuate surface, means for supporting said deflector from said ring and for positioning the lowermost portion of the arcuate surface of the deflector slightly below the lower perimetral edge of said ring, a 15 preheating fuel coil mounted on said deflector in spaced relation with the inner wall of said ring, a burner positioned in spaced relation beneath said deflector and connected to said coil, and means on the under arcuate surface of the deflector disposed above the lower perimetral edge of 20 said ring for timing the initial flame combustion of the fuel issuing from the burner.

2. In an oil burner assembly, the combination of a burner, a baffle having a convex under surface disposed above the burner for distributing the combustible gases issuing therefrom, a fuel supply coil wound in a helix about the baffle and having its lower end connected to the burner, lugs on the perimetral surface of the baffle under supporting the coil, and means below said lugs for reducing the velocity of a portion of the combustible gases to maintain initial flame combustion thereof between said lugs and said means.

3. In an oil burner assembly, the combination 35 of a flame guiding ring, a deflector positioned axially of the ring and supported therefrom for distributing the combustible gases within said ring, a burner disposed beneath the deflector, a fuel supply coil disposed about and supported by the 40 deflector and having its lower end connected to the burner, and means on said deflector below said coil for reducing the velocity of a portion of the combustible fuel to maintain initial flame combustion thereof between said coil and said means.

4. In an oil burner assembly, a unitary structure comprising a deflector arranged to distribute combustible gases, a preheating fuel coil surrounding the deflector and supported thereby, a burner positioned beneath the deflector and supported by the lower end of the coil, and means on said deflector below said coil for reducing the velocity of a portion of the combustible fuel to maintain initial flame combustion thereof between said coil and said means.

5. A deflector for use with a burner which comprises a body portion having an under arcuate portion arranged to be positioned in the path of the combustible gases issuing from the burner to distribute the same, an arm for supporting said 60 body portion, the under side of said arm extending upwardly adjacent the said body portion to prevent the flame from extending along said arm.

6. A deflector arranged to be positioned over a burner which comprises a cylindrical body portion having an under arcuate surface for distributing the combustible gases issuing from the burner, an arm having a depending flange of downwardly converging cross section for supporting the deflector, the lower edge of said flange extending upwardly to said body portion to prevent the flame from extending along the bottom of said flange.

7. In an oil burner, the combination of a fuel jet, a deflector against the surface of which the 75

5 combustible gases of the fuel impinge, the said surface being substantially semispherical, and means disposed on said surface to control the combustion timing of a portion of the flame of burning fuel by reducing the velocity of a part of the combustible gases to a point where the propagation is maintained immediately above said means.

10 8. A deflector member to be disposed above an oil burner and having a convex lower surface against which the combustible gases of the fuel impinge, and means on said deflector disposed above the apex thereof for reducing the velocity of a part of the combustible gases to maintain initial flame combustion of the fuel at a point in the immediate region above said means.

15 9. A deflector member to be disposed above an oil burner and having a convex lower surface against which the combustible gases of the fuel

impinge, and a plurality of spaced projections arranged about the perimetral surface of the deflector member above the apex thereof for reducing the velocity of a portion of the combustible gases to maintain initial flame combustion of the fuel at a point in the immediate region above said projections.

10 10. A deflector member to be disposed above an oil burner and having a convex lower surface against which the combustible gases of the fuel impinge, and a plurality of spaced projections on the convex surface of the deflector member above the apex thereof for reducing the velocity of a part of the combustible gases to maintain initial flame combustion of the fuel at a point in the immediate region above said projections, said projections being at all times below the zone of combustion.

FRANK W. OFELDT.
